UNITED STATES PATENT OFFICE

132,105

DESIGN FOR A COUNTER STOOL OR SIMILAR ARTICLE

Isaac Peterson, Oakland, Calif.

Application March 17, 1941, Serial No. 99,657

Term of patent 7 years

To all whom it may concern:

Be it known that I, Isaac Peterson, a citizen of the United States, residing at Oakland, in the county of Alameda and State of California, have invented a new, original, and ornamental Design for a Counter Stool or Similar Article, of which the following is a specification, reference being had to the accompanying drawing, forming part thereof.

Figure 1 is a perspective view of the counter stool or similar article, showing my design; and

I claim:

The ornamental design for a counter stool or similar article, as shown.

ISAAC PETERSON.
